United States Patent Office

Des. 177,902
Patented June 5, 1956

177,902

TELEVISION LAMP

Sam Derico, Cleveland, Ohio

Application August 23, 1955, Serial No. 37,633

Term of patent 7 years

(Cl. D48—20)

Fig. 1

Fig. 2

Fig. 3

Fig. 4

Figure 1 is a perspective view of a television lamp showing my new design;

Figure 2 is a top plan view thereof;

Figure 3 is a rear elevational view thereof; and

Figure 4 is a side elevational view of the same.

The dominant features of my design are shown in solid lines.

I claim:

The ornamental design for a television lamp, as shown and described.
